The ornamental design for a rake, as shown and described.

DESCRIPTION
